United States Patent Office

Des. 188,856
Patented Sept. 20, 1960

188,856

ILLUMINABLE GAME DEVICE

Carey F. Woods, 5800 McCommas, Dallas, Tex.

Filed Nov. 25, 1957, Ser. No. 48,643

Term of patent 14 years

(Cl. D34—5)

FIG. 1

FIG. 2

FIG. 3

Fig. 1 is a side elevational view of the illuminable game device showing my new design.

Fig. 2 is a perspective view of the device shown in Fig. 1.

Fig. 3 is an end elevational view of the device shown in Figs. 1 and 2.

The drawing is shaded to represent contrasting appearance, the characteristic features of the design being shown by means of full lines in the drawing.

I claim:

The ornamental design of an illuminable game device, as shown and described.
